F. L. YERGES

BIAS BUFFER

Filed Aug. 27, 1925

UNITED STATES PATENT OFFICE.

FRANK L. YERGES, OF FREMONT, OHIO; AMELIA N. YERGES, EXECUTRIX OF SAID
FRANK L. YERGES, DECEASED, ASSIGNEE TO THE YERGES MANUFACTURING COM-
PANY, OF FREMONT, OHIO, A CORPORATION OF OHIO.

BIAS BUFFER.

Application filed August 27, 1925. Serial No. 52,775.

This invention relates to buffing and the sections or wheels of fabric for delivering abrasive and the manufacture of such sections.

5 This invention has utility when incorporated in plies integral for greater than ply area and preferably bias cut and pleated or folded into approximate ply area, and the assembling of such plies into sections.

10 Referring to the drawings:

Fig. 1 is a view of a bias cut blank as cut from strip stock, as canvas duck;

15 Fig. 2 is a pleated stitch assembled ply as untrimmed and formed from the blank of Fig. 1;

Fig. 3 is a section of assembled plies, parts being broken away;

Fig. 4 is an edge view of a section, parts being broken away; and

20 Fig. 5 is a view showing a wheel made up of such sections and mounted for use.

25 Strip material 1 is shown as having opposite edges 2, 3, from which extend diverging cuts 4 to parallel cuts 5 thereby completing the long strip 6 as a blank with tapered ends 7. Blank strip 6 is folded on itself herein by pleating to approximately one-third its length, comprising pleats 8 perpendicular to the edges 5, which pleats are parallel to each

30 other, and are assembled by stitching 9 parallel to each other and approximately at right angles to the folds or pleats 8. These folds 8 may in practice be formed by a pleating machine and the stitches 9 run by

35 a multiple needle stitcher for producing such stitches simultaneously in parallel across the ply as folded to approximate ply area. These pleated and stitched plies 10 are placed, as to the folds 8, at a slightly

40 angularly shifted position and assembled between outer plane plies 11 by stitching 12, 13. These stitches 12 are parallel and intersect the parallel stitches 13 at approximately right angles to result in a criss-cross

45 structure. Such assembled sections are trimmed to circular form and central opening 14 provided for mounting on arbor 15 against collar 16 to be held in position by washer 17 set up by nut 18. Bearings 19

50 mount arbor 15 with driving pulley 20 to be

actuated by belt 21. The bearings 19 are mounted on jack-frame 22.

In building up a buffer section from a pleated ply, as herein, a pleated ply may be the equal of three single plies and a section 55 may be built up say of seven pleated plies, and the outer plain or binding plies to have the equivalent in material of a twenty-three ply section. These sections are of approximately uniform character radially as to the 60 quantity of fabric. The labor of production is not in excess of similarly stitch-assembled flat ply sections of the same quantity of cloth. The bias cuttings for the blanks are effected, as herein disclosed, with 65 a reduction in the total waste and reduction in the cost of cutting which may be done three times as fast as the plain disk buff.

There is a gain in assembly, due to the 70 fewer number of plies. The labor of the folding or pleating and the pleat laying stitches 9 about offsets the handling of the greater number of plies and the grouping thereof. The resulting structure is one wherein the bias cutting of the sheet material 1 as to the warp 23 and woof 24, is such that at the entire periphery of the folded or pleated ply there is fray-out resisting bias margin. The termini of the folds 8 are symmetrically grouped and provide additional 75 80 composition or adhesive carrying pockets in peripheral series in addition to the pockets provided by the criss-cross stitching 12, 13.

The resulting section is bias as to the 85 peripheral exposure of the plies with the folds or pleats so distributed and held by the stitchings, that there may be no catching of the material being acted upon therein to be pulled from the hands of the operator. Such material whether of aluminum, brass, 90 or other sheet or cast metal is quickly acted upon herein for an output or life of the wheel from two to three times that of the same material as assembled independently of the pleating or folding. Accordingly, 95 there is efficiency and economy hereunder. The cutting saving runs from two to three percent. The operation increases economy at least one hundred percent over the plain ply type of section. The folds are sym- 100

metrical and the stitchings are symmetrical for disk rotation in either direction. The bias is uniform for the entire radial extent of the disk.

5 What is claimed and it is desired to secure by United States Letters Patent is:

1. A buffing wheel ply made from a blank, the marginal edges of which blank are bias

cut in respect to the weave, said blank being folded into parallel pleats so that the resultant form of ply is substantially circular. 10

2. A buffing wheel section made up of parallel pleated plies, each ply being placed at an angle with respect to its adjacent plies.

In witness whereof I affix my signature.

FRANK L. YERGES.
